(57) CLAIM

The ornamental design for a recreational trailer, as shown and described.

DESCRIPTION

FIG. 1 is a perspective view of a recreational trailer design; FIG. 2 is a perspective view of the recreational trailer in FIG. 1;

FIG. 3 is a side view of the recreational trailer in FIG. 1;
FIG. 4 is a side view of the recreational trailer in FIG. 1;
FIG. 5 is a front view of the recreational trailer in FIG. 1;
FIG. 6 is a back view of the recreational trailer in FIG. 1; and,
FIG. 7 is a top view of the recreational trailer in FIG. 1.

It will be understood that the dashed lines presented in the drawings are for illustration only, and do not form a part of the claimed design.
